UNITED STATES PATENT OFFICE.

EDWARD ERICKSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

TRIMMING MACHINE.

Application filed June 21, 1919. Serial No. 305,731.

To all whom it may concern:

Be it known that I, EDWARD ERICKSON, a citizen of the United States, residing at Beverly, in the county of Essex and State 5 of Massachusetts, have invented certain Improvements in Trimming Machines, of which the following description, in connection with the accompanying drawings, is a specification, like reference characters on 10 the drawings indicating like parts in the several figures.

This invention relates to trimming machines and more especially to those adapted to operate on boots and shoes.

15 In the manufacture of boots and shoes that would be seriously damaged by being soiled or discolored, the uppers are, in some cases, covered by protectors made of some relatively thin sheet material such as cloth 20 or paper. When such protecting covers are used they are applied to the uppers before the shoes undergo lasting and remain on the shoes until the latter are otherwise completed and ready to be packed. Incidentally 25 to attaching the margin of the upper to the sole the protecting cover is caught by the stitches or other fasteners, so that considerable difficulty ensues in connection with the removal of the cover. Heretofore it has 30 been the practice to remove the visible part of the cover by first slashing the latter from top to bottom at the toe and heel, turning down the sections divided by slashing, and finally by drawing a scoring knife manu- 35 ally along that portion of the cover that lies on the sole-extension. This manual scoring operation is not entirely satisfactory, partly because the scoring knife sometimes injures the shoe, partly because it is difficult if not 40 impossible to trim the cover closely enough to the crease formed by the upper and the sole-extension, and partly because it requires considerable time and skill on the part of the operatives. So far as I am aware no 45 machine for performing this operation has ever been successful although some attempts have been made to provide a satisfactory machine for the purpose.

In view of the aforesaid problem and difficulties the principal object of the present invention is to provide a satisfactory machine for scoring or severing a shoe cover.

In accordance with this object a feature of the invention consists in a machine hav-

ing a scoring knife constructed, arranged 55 and operated so as to score or sever a shoe cover in the crease formed by the upper and the sole-extension, without liability of injuring the shoe or of leaving any remnant of the cover projecting from the crease far 60 enough to be observed.

Another object is to provide a machine that will trim the cover more rapidly than is possible with manual trimming, without imposing any undue fatigue upon the operative 65 and without subjecting the work to undue vibration.

While the invention as shown by the accompanying drawings is illustrated as being embodied in what I consider to be the 70 preferred form it is not limited, in its broad aspects, to the design shown. According to the illustrated embodiment the scoring or severing knife is operated so as to engage the work intermittently and preferably by striking a series of percussional impacts to penetrate the work without appreciably vibrating the latter. The invention also preferably includes a guard against 75 which the shoe may be held and relatively 80 to which it may be fed by the hands of the operative. The guard, moreover, as shown, is arranged to overhang the knife and to lie between the knife and the shoe-upper so as to bear on the latter. The tip of the guard 85 bears on that part of the shoe-cover that lies on the upper surface of the sole so as to limit the penetration of the knife.

Another feature of the invention consists 90 in novel means for imparting operating motion to the knife. According to the form illustrated the knife is moved to penetrate the work and is otherwise moved, while penetrating, to execute a drawing cut, the operating edge therefore having a compound 95 motion. The scoring or cutting edge of the knife, according to this embodiment of the invention, is caused to describe an endless curved path through the greater portion of which it is clear of the work and behind the 100 guard. Because of the thinness of shoe-covers the knife is preferably so operated, and the knife and guard are preferably so related, that the extent of drawing cut in each cycle will be considerably greater than 105 the depth of penetration. Accordingly, the invention, as shown, is embodied in a machine that fulfills these conditions. The

- construction of the operating parts is such that they may operate at very high speed, and although the knife does not engage the work continuously the latter may be fed 5 continuously and rapidly without interrupting the continuity of the scoring cut; and without departing from the crease even where the latter curves sharply as at the ends and at the ball portion of the shoe.
- 10 Since, in trimming along the sharply curved portions, ample clearance between the knife and the work is desirable, and since excessive vibration of the machine is something to be avoided, an object of the invention 15 is to provide knife-operating mechanism that will insure the desired margin of clearance with a minimum degree of vibration. Accordingly, these considerations are taken into account in the illustrated form of 20 the invention in which the knife is caused to execute an elliptic motion of which the major component includes penetration and clearance while the minor component causes the drawing cut. Moreover, as shown, the 25 operating mechanism causes the drawing action to be effective so long as the knife is in contact with the work, and consequently it becomes effective simultaneously with the beginning of each penetration.
- 30 These and other features of the invention are illustrated by the accompanying drawings and are hereinafter described in detail and claimed.

Referring to the drawings,—

- 35 Fig. 1 represents a side elevation, partly broken away, of a machine embodying the present invention, the upper portion of the head being shown in vertical section;

40 Fig. 2 represents a cross-section through the structure intersected by line 2—2 of Fig. 1;

45 Fig. 3 represents a sectional view similar to Fig. 1 but on a larger scale of the scoring knife and the elements adjacent thereto, and includes a portion of a shoe in position to undergo operation;

50 Fig. 4 represents a section through the structure intersected by line 4—4 of Fig. 3; and

55 Fig. 5 represents a section through the structure intersected by line 5—5 of Fig. 3.

Fig. 6 represents an elevation of the work-engaging portions of the knife and knife-guard.

60 The machine as shown comprises a base or standard 10 and a frame or head 12 affixed thereto. The scoring knife is indicated at 14, and it is shown in the present instance as embodying an arcuate form for purposes hereinafter explained. One end of the knife is beveled to form the scoring or severing edge. The knife is detachably and adjustably fastened to a holder or carrier 16 which in the present instance has a shank portion 18 that constitutes a rockshaft. The

portion indicated at 16 has an internal cylindrical groove 20 of the same degree of curvature as the knife and the latter is seated therein and clamped by a bolt 22 and a clamping bar 24. The holder 16 is bored and tapped to receive the shank of the bolt and the shank extends loosely through a hole in the bar 24. This bar bridges across the concavity of the knife holder and one end is seated upon the knife while the other end is seated in the groove 20 so as to be locked against rotation about the axis of the bolt. When the bolt is loosened the knife may be adjusted lengthwise or may be removed for sharpening or replacement.

70 The shaft portion 18 of the knife-holder extends through a sleeve 26 and is retained in the sleeve by the hub 28 of an arm 30. This hub may be pinned or otherwise rigidly fastened to the shaft portion. End-shake of the rock-shaft is prevented by a collar 32 formed thereon and arranged to bear against the lower end of the sleeve 26. The outer end of the arm 30 is movably connected to a fixture or anchoring pin 34 through the medium of a block 36. The pin 34 as shown is screwed into the frame of the head 12 and the block 36 is mounted thereon so as to be free to swivel. The arm 30, as shown by Fig. 2, is forked and is arranged to embrace the block.

75 The bore of the sleeve 26 is eccentric and the sleeve is rotated about its axis so as to carry the rock-shaft bodily about said axis. Any suitable means may be provided for rotating the sleeve, the means shown comprising a pulley 38 affixed to the upper end of the sleeve, and a belt 40 running from said pulley to a driving pulley 42. For the convenience of the operative the sleeve 26 and rock-shaft 18 are inclined, and since the shaft 44 that carries the driving pulley 42 is horizontal idle pulleys such as that indicated at 46 are arranged to guide the belt. The sleeve 26 bears in a hardened steel 80 bushing 48 and the latter is fixed by any suitable means in a bore in the head. End-shake of the sleeve is prevented by a shoulder 50 at the lower end and by the hub of the pulley at the upper end. The head is provided with an oil cup 52 from which oil is conducted to the sleeve by a duct 54 that extends through the bushing.

85 As the sleeve is rotated it carries the rock-shaft 18 bodily in a circular path the diameter of which depends upon the degree of eccentricity between the axis of the sleeve and that of the rock-shaft. The bodily movement thus imparted to the knife is 90 translated into elliptic motion of the scoring edge in consequence of the connection between the rock-shaft and the anchoring pin 34. According to the arrangement shown the scoring edge of the knife is approximately midway between the axis of the 95

sleeve and that of the anchoring pin, with the result that the lateral movement of the knife is only one-half as great as the movement toward and from the plane of the work.

5 Figure 3 includes a portion of a shoe to which a protecting cover has been attached. The upper of the shoe is indicated at 56 and the sole-extension is indicated at 58. The protecting cover is indicated at 60 and it is shown as having been turned down from the upper preparatory to being severed. It is to be noted that the inner marginal portion of the cover is held by the stitches that connect the sole to the upper, one of said 10 stitches being indicated at 62. In practice the shoe is presented to the knife in such relation that the scoring edge of the knife will operate in the crease formed by the upper and the sole-extension, but in order to guide 15 the work relatively to the knife and to guard the work against injury the machine is provided with a guard 64. This guard as shown is affixed to the head 12 by screws one of which is indicated at 66. The tip of the 20 guard is beveled to a thin edge and is arranged to bear on that portion of the cover 60 that lies on the sole-extension. The guard also bears on the upper adjacent to the sole-extension and when the shoe is undergoing 25 operation the guard lies between the knife and the shoe-upper. The knife will preferably be adjusted relative to its holder so that its scoring edge will never project beyond the tip of the guard more than enough to cut through the cover 60, and consequently the knife will be fully out of contact with the work through the greater 30 portion of its cycle.

In order to enable the knife to trim in the 40 crease along the incurve of the shank portion of the shoe the outer surface of the guard is preferably convexed to a degree commensurate with the greatest degree of concavity to be encountered in the shank 45 portions of shoes. The shoe may be tipped so as to have the plane of the sole more nearly vertical, when necessary, to enable the knife to enter the less accessible portions 50 of the crease. A very light pressure of the sole-extension against the tip of the guard is sufficient to insure penetration of the cover 55 by the knife because the latter will operate at very high speed and will penetrate by impact before it can overcome the inertia of the shoe.

The arcuate form of the knife, as shown, is preferable because it permits the clamping bolt 22 and bar 24 to be located out of the way of the guard and to be of ample proportions to hold the knife without danger of working loose. Furthermore, this structural feature permits the upper part of the guard to diverge away from the shoe without obstructing the bodily movement of the head 16 of the knife-holder.

Having described my invention, what I claim as new and desire to secure by Letters Patent of the United States is:—

1. A machine of the character described comprising a scoring knife arranged to score 70 the work in the crease formed by the upper and the sole-extension of a shoe, and means arranged to operate the knife so as to cut repeatedly through the cover material lying on the sole-extension. 75

2. A machine of the character described comprising a bodily movable knife arranged to score the work in the crease formed by the upper and the sole-extension of a shoe, and means arranged to operate the knife so 80 as to engage the work intermittently.

3. A machine of the character described comprising a bodily movable knife arranged to score the work in the crease formed by the upper and the sole-extension of a shoe, 85 and means arranged to operate the knife so as to cause the scoring edge to describe an endless path tangential to the upper surface of the sole-extension.

4. A machine of the character described comprising a scoring knife arranged to score 90 the work in the crease formed by the upper and the sole-extension of a shoe, and means arranged to operate the knife so as to cause the scoring edge to engage the work intermittently and to describe an endless path 95 tangential to the sole-extension.

5. A machine of the character described comprising a scoring knife, means arranged to coact with the sole-extension of a shoe 100 to guide the latter relatively to the knife, and means arranged to operate the knife so as to cause a relatively slight penetrating movement and a relatively long drawing cut. 105

6. A machine of the character described comprising a bodily movable scoring knife, means arranged to guide a piece of work relatively thereto, and means for causing the knife to operate on the work intermittently by executing relatively slight penetration and a relatively long drawing cut for each cycle. 110

7. A machine of the character described comprising a knife having a cutting edge arranged to operate in the crease formed by 115 the upper and the sole-extension of a shoe, a guard arranged to coact with the sole-extension to locate the latter relatively to said knife, and means for operating the knife so as to cause a relatively slight penetrating 120 movement and a relatively long drawing cut.

8. A machine of the character described comprising a scoring knife, means for guiding the work relatively thereto, and means for operating the knife so as to cause it to 125 penetrate the work intermittently and to execute a drawing cut while penetrating.

9. A machine of the character described comprising a knife having a scoring edge, means for guiding the work relatively there- 130

- to, and a means for operating the knife so as to impart penetrative and other operating movement thereto.
10. A machine of the character described comprising a scoring knife arranged to score the work in the crease formed by the upper and the sole-extension of a shoe, and means arranged to operate the knife so as to cause the scoring edge to describe an elliptic path tangential to the sole-extension.
11. A machine of the character described comprising a scoring knife arranged to score the work in the crease formed by the upper and the sole-extension, a guard arranged to bear on the upper and on the work to be severed, and means arranged to thrust the knife repeatedly through the work lying on the sole-extension.
12. A machine of the character described comprising a scoring knife arranged to score the work in the crease formed by the upper and the sole-extension, means arranged to operate the knife, and a guard arranged to limit the penetration of the knife.
13. A machine of the character described comprising a scoring knife arranged to score the work in the crease formed by the upper and the sole-extension, means arranged to thrust the knife repeatedly toward the sole-extension, and a guard arranged to bear on the upper and on the work lying on the sole-extension so as to locate the latter relatively to the knife.
14. A machine of the character described comprising a scoring knife arranged to score the work in the crease formed by the upper and the sole-extension, means arranged to operate the knife, and a guard arranged to lie between the knife and the shoe-upper and having a convex upper-engaging surface so formed as to permit access of the knife to the crease in the incurved shank portion of the shoe.
15. A machine of the character described comprising a rock-shaft, a scoring knife carried thereby, and means arranged to oscillate the rock-shaft and to move it bodily so as to impart a compound motion to the knife.
16. A machine of the character described comprising a rockshaft, a scoring knife carried thereby, and means arranged to oscillate the rockshaft about its axis and to move it bodily about another axis so as to impart a compound motion to the knife.
17. A machine of the character described comprising a rockshaft, a scoring knife carried thereby, means arranged to carry the rockshaft bodily about an axis other than its own and to move it synchronously about its own axis so as to impart a compound motion to the knife.
18. A machine of the character described comprising a rotary driven member having an eccentric bore, a tool-holder carried by said member and having a shaft portion arranged in said bore, a tool carried by said tool-holder, and means arranged to hold said tool-holder against turning with said rotary member.
19. A machine of the character described comprising a rotary driven member having an eccentric bore, a rockshaft carried by said member and arranged in said bore, a tool carried by said rockshaft, an element relatively to which said member is movable, and means connecting said element and said rockshaft so as to cause oscillatory motion of the latter in consequence of rotation of said driven member.
20. A machine of the character described comprising a rotary sleeve and a bearing structure therefor, the bore of said sleeve being eccentric, a rockshaft extending through and bearing in said bore, a tool carried by said rockshaft, means for rotating the sleeve, and means arranged to oscillate the rockshaft in consequence of the bodily movement imparted to the latter by rotation of the sleeve.
21. A machine of the character described comprising a bodily movable knife arranged to operate in the crease formed by the upper and the sole-extension of a shoe, a fixed guard arranged to bear on the material to be severed from the shoe, and means for operating said knife so as to project the operating edge beyond and to retract it behind said guard.
22. A machine of the character described comprising a bodily movable knife arranged to operate in the crease formed by the upper and the sole-extension of a shoe, fixed means arranged to co-operate with the sole-extension to locate the material to be operated on by the knife, and means for operating the knife so as to cause the operating edge thereof to strike a series of percussional impacts against the material between said fixed means and the sole-extension.
23. A machine of the character described comprising a movable blade-holder, an arcuate knife-blade having an operating edge at one end arranged to operate in the crease formed by the upper and the sole-extension of a shoe, said holder having a concave surface against which the convex surface of the blade is seated, means co-acting with the concave surface of the blade to clamp the latter to the holder, and means for actuating the blade-holder to operate the blade.
24. A machine of the character described comprising a movable blade-holder, an arcuate knife-blade having an operating edge at one end arranged to operate in the crease formed by the upper and the sole-extension of a shoe, means for fastening the blade to the holder in such relation that the shank portion of the blade curves away

from the shoe-upper, and means for actuating the blade-holder to operate the blade.

25. A machine of the character described comprising an arcuate knife-blade arranged to overhang the sole-extension of a shoe and having an operating edge at one end arranged to operate in the crease formed by the upper and sole-extension, a curved guard formed and arranged to overhang the knife 10 and to bear against the shoe-upper adjacent to said crease, and means for operating the knife, the machine being organized to provide an unobstructed space in which the shoe may be manipulated so as to keep the 15 point of operation in said crease.

26. A machine of the character described comprising a blade-holder having an internal semi-cylindric groove, an arcuate blade arranged in said groove and having an operating edge at one end, a clamping member portions of which are arranged to bear respectively on the concave surface of the blade and on the semi-cylindric surface of 20 said groove behind the rear end of the blade, means arranged to cause said member to 25 clamp the blade to the holder, and means for actuating the holder to operate the blade.

In testimony whereof I have signed my name to this specification.

EDWARD ERICKSON.
